SEWING MACHINE FOR FUR AND THE LIKE

Thomas C. Mladinich, New York, N. Y.

Application April 16, 1937, Serial No. 137,315

14 Claims. (CL 112—16)

The purpose of this invention is to provide improvements in machines for sewing fur and similar products, in which the wearing parts are improved to compensate for the increased speed 5 at which these machines now operate, and also in which means is provided for constantly oiling all of the wearing parts.

The invention is a sewing machine of the type used for sewing fur and similar products, in 10 which the respective parts and movements are operated through a main driving shaft, and the various movements are obtained by eccentrics, cams, and sliding blocks. These machines were normally designed to operate at a relatively low 15 speed, however, at present it is required to operate them at about twice the original speed, so that the wear is increased, and the parts, as originally designed, do not stand up under this hard service.

20 It has, therefore, been found necessary to make certain changes in the parts in order to reduce the wear to a minimum, and also so that the parts will stand up under the increased speed.

25 This machine is improved by mounting the main shaft in ball bearings, installing the main operating cam in a sliding block so that the cam surface is in continuous engagement at all times, by increasing the size of the mounting parts of 30 the needle bar, slidably holding the guide portion of the looper frame on a block instead of the usual pin, increasing the length of the bearing of the looper rocker bracket, placing the feed disc pressure spring in a position aligned with the 35 feed disc arm, improving the clutch and brake, and incorporating a lubricating system in the frame which automatically pumps oil to the upper part thereof from where it flows downward upon the moving parts.

40 The looper frame has heretofore been moved backward and forward by an eccentric engaging flat surfaces of a yoke thereof, and as this provides a two-point contact only, it has been found necessary to place a sliding block on the eccentric, thereby providing a continuous wearing surface 45 between the eccentric and block, and also providing a snug sliding movement between the block and looper frame. The looper bar and the oscillating arm in which it is held are relatively small and present comparatively small 50 wearing surfaces, and as this is subjected to an extreme thrust load it has been found necessary to increase the wearing surface between the parts thereof. The fork at the rear of the looper 55 frame normally slides over a pin, providing a small wearing surface and, therefore, it has been found necessary to place a block on the pin, thereby materially increasing the wearing surfaces. The feed disc arm is resiliently held in 60 ward by a spring, and this is connected to the

arm by levers, and as the size of the casing is relatively small, it is necessary to use a comparatively short lever arm by which the spring is connected to a foot lever to move the feed disc outward, and as the pressure required is objectionable to the average operator, the position of the spring is changed, so that it is possible to increase the length of the lever, thereby providing means for reducing the pressure required to operate the feed disc, and at the same time locating the spring where it provides a direct action on the said feed disc arm. The needle bar yoke has formerly been mounted on a single rod, and as it is moved backward and forward by an eccentric, it moves from side to side and the wearing parts receive comparatively hard service, so that another bar has been added, providing a two-point support and an independent mounting, reducing the wearing to a minimum. And whereas the main shaft operates successfully at low speed, it has been found necessary to re-design the mounting, placing ball bearings in both sides of the frame, and also at the belt wheel at the outer end of the shaft.

25 The object of the invention is, therefore, to provide improvements in machines for sewing fur and the like by increasing the wearing surfaces of the parts thereof to compensate for increased speed of the machines.

Another object is to provide means for increasing the wearing surfaces of fur sewing machines without increasing the size of the main frame.

Another object is to provide means for increasing the wearing surfaces of the parts of fur sewing machines by utilizing substantially all 35 of the same parts.

Another object is to provide means for mounting the main shaft of fur sewing machines in ball bearings without increasing the size of the main frame.

Another object is to provide means for automatically lubricating the parts of a fur sewing machine.

40 A further object is to provide lubricating means for a fur sewing machine, which may be installed in the frame of machines without increasing the size thereof, and in which all of the operating parts may be contained within the main frame.

45 A still further object is to provide means for increasing the wearing surface of the looper bar mounting without changing the size of the frame in which it is mounted.

50 And a still further object is to provide means for improving fur sewing machines by increasing the wearing parts to compensate for increased speed, all of which are comparatively simple and inexpensive.

55 With these ends in view the invention embodies a fur sewing machine in which the wearing surfaces

faces of the cams, eccentrics, and substantially all of the moving parts have been increased without increasing the size of the main frame in order to compensate for increased speed.

5 Other features and advantages of the invention will appear from the following description, taken in connection with the drawings, wherein:

10 Figure 1 is a view showing a side elevation of the machine with part broken away showing the lubricating pump.

15 Figure 2 is a view looking toward the opposite side of the machine with part broken away, showing the clutch.

20 Figure 3 is a cross section looking in the same direction as Figure 2, and taken substantially on line 3—3 of Figure 4, with parts omitted.

25 Figure 4 is a longitudinal section through the machine taken substantially on the center line of the main shaft, with part of the eccentrics and cams shown in full.

30 Figure 5 is a plan view with parts broken away, and parts omitted.

35 Figure 6 is a detail showing a front view of the clutch.

40 Figure 7 is a detail showing the improved mounting of the needle bar yoke.

45 Figure 8 is a similar view showing an alternate type of mounting for the needle bar yoke.

50 In the drawings the device is shown as it may be made, wherein numeral 1 indicates the main frame, numeral 2 the main shaft, numeral 3 the looper frame, numeral 4 the needle bar yoke, numeral 5 the clutch, and numeral 6 the lubricating pump.

55 The main frame is substantially the same as has been used heretofore, and this consists of four substantially straight walls 7, 8, 9, 10, with an extending part 11 at the front, in which the clutch and brake are mounted, and this part is covered by a cap 12, and the main frame by a cover 13. It will be understood, however, that the frame may be of any type or design, and may be arranged in any manner.

60 In the design shown in Figure 4 the frame is provided with a boss 14 in the side 9, and an extended boss 15 in the side 8, and the main shaft 2 is rotatably mounted in the bosses 14 and 15 by ball bearings 16, 17, and 18. The bearing 16 is covered by a cap 19, and the bearing 18 by a cap 20. It will be noted that the bearing 16 is held against a shoulder 21 on the shaft 2 by a nut 22, and the bearings 17 and 18 are held against a shoulder 24 by a nut 25 and sleeves 26 and 27. In this design the belt wheel 28 is mounted upon the sleeve 27, however, it will be understood that this may be mounted directly upon the shaft or in any manner. It will also be understood that the shaft may be mounted in bearings of any other type or the arrangement of the ball bearings may be changed, as may be desired.

65 The looper frame 3, which is shown in detail in Figure 3, is formed with downwardly extending members 29 and 30, and the looper frame eccentric 31, which is mounted on the shaft 2, is mounted between the members 29 and 30 through a sliding block 32 having flanges 33 and 34 at the sides which engage the sides of the members 70 29 and 30, and the lower ends of the members 29 and 30 are connected by a bolt 35 by which slight wear between the block and members 29 and 30 may be taken up. The looper 36 is mounted in the looper chuck shell 37 on the outer end 38 of the shaft 39, and the outer end of the shaft

is provided with a shoulder 40 adapted to engage the end 41 of the frame 3 to take the inward thrust of the looper, and this surface has been increased to compensate for the wear thereof. The shaft 39 extends into the frame, and the 5 looper oscillating arm 42 is secured to the shaft, and it will be noted that the forward end of the arm 42 is provided with a boss 43 which engages the end 44 of the forward part of the frame 3, providing a relatively large bearing surface to 10 increase the wear therebetween. A pin 45 extends outward from the arm 42 as shown in Figure 4, and this extends into a ball 46 in a cam groove 47 in an oscillating cam 48, and it will be noted that as the cam rotates it will twist the 15 shaft 39 through the arm 42. The upper rear corner of the frame 3 is formed with a fork having upper and lower sides 49 and 50 and a sliding block 51 is mounted between the sides 49 and 50 of this fork on a bolt or pin 52, the bolt 20 52 being mounted between the ears 53 and 54 extending upward from the back 8 of the main frame 1. The lower forward corner of the frame 3 is provided with a hub 55 through which it is mounted on a pin 56 of the looper frame rocker 25 57, and the rocker is formed on the end of a shaft 58, which is rotatably mounted in a looper rocker bracket 59, which is held on the front 7 of the machine by bolts 60 and 61. The hub 55 of the frame 3, and also the hub of the bracket 59 30 have been materially lengthened to compensate for wear, thereby providing substantial bearing surfaces in these parts. It will be noted that as the shaft rotates the eccentric 31 will move the looper frame backward and forward, and with 35 the opposite corners held between the pin 52 and the rocker 57, this frame will have an oscillating movement, and at the same time the cam 48 will turn the looper, through the groove 47 and ball 46.

40 The needle yoke 4 is formed as shown in Figure 7, with a back plate 62 having ends 63 and 64, and hubs 65 and 66, with their forward surfaces formed with slots 67 and 68. The upper and lower parts are held by bolts 69, 70, 71, and 72, so that any slight wear therein may readily be taken up by screwing the bolts or screws inward. The upper hub is fixedly attached to the needle bar 73 on the outer end of which the needle is mounted, and the lower hub 66 is slidable on a stationary shaft 74. The forward end of the bar 73 is slidably mounted in a special bearing 75 which is adapted to eliminate wear between the bar and frame. The yoke 4, formerly mounted on a single upper shaft similar 55 to the shaft 73, is moved backward and forward by the needle bar yoke eccentric 76 mounted on a shaft 2, and this causes a twisting movement and side play wearing the sides thereof, whereas, with the lower end slidable on the shaft 74, side 60 play is eliminated and an independent mounting provided.

65 This device may also be made as shown in Figure 8, in which a sliding block 77 is provided between the eccentric, which is indicated by the 65 numeral 78, and the yoke 4, and it will be noted that this provides a continuous bearing on the outer surface of the eccentric and a sliding contact between recesses 79 and 80 in the edges of this block, and the inner surfaces of the members 63 and 64. The feed disc arm 81 is mounted on two shafts 82 and 83 through a base 84, and these shafts are slidably held in the frame, and the arm is resiliently held inward by a spring 85, one end of which is held on a bolt 86 extend-

ing inward from the base 84, and the opposite end is held on a bolt 87 on which is a thumb nut 88, by which the bolt may be moved inward or outward to adjust the tension on the spring. 5 The lower shaft 83 is formed with a flat space 89 and a yoke 90 of the pressure lever 91 extends upward through the space 89 and is adapted to move the arm 81 forward as a lever 92 on the opposite end of the member 91 is drawn downward. 10 In Figure 1 a chain 93 is shown attached to the outer end of the lever 92, and this chain may be connected to a foot lever or any suitable means by which it may be drawn downward. The pressure lever 91 is pivotally mounted on a 15 shaft 94 which extends through the frame, as shown.

The clutch 5 is preferably made as shown in Figure 2, and this is operated by an eccentric 95 on the shaft 2, which operates in a hub 96 of an 20 arm 97, and the lower end of the arm is connected by a pin 98 to a lever 99 which is pivotally mounted on a pin 100 through a slot 101, and the pin is slidably mounted in a slot 102 in the main frame 1. The opposite end of the lever 99 25 is connected by a pin 103 to the clutch operating bar 104, and it will be noted that as the eccentric 95 moves the arm 97 upward and downward, this will raise and lower the end of the lever 99, and this will, in turn, raise and lower the opposite 30 end of the lever and operate the clutch. The movement of the clutch may be adjusted by moving the pin 100 back and forth in the slot 102, and it will be noted that the pin is adjustably held by a lock nut 105 on the outer end, and the 35 inner end is held in the lever 99 by a nut 106. A block 107 is provided on the pin 100, and this is formed with a section 108 having flat sides which engage the surfaces at the sides of the slot 100 of the lever 99, and it will be noted that 40 with this block pivoted on the pin 100, it will be free to twist with the movement of the lever 99, thereby permitting free movement thereof, and at the same time permitting adjustment in the movement. The pin 100 may also be provided 45 with a pointer 109 to indicate the position or movement from the exterior of the main frame.

The clutch bar 104 is formed with a yoke 109 at the inner end, and this is provided with a bolt 110, at the open ends, and with a sliding block 111 on the shaft 112, upon which the bar is 50 mounted. The bolt 110 may be tightened to take up slight wear in this connection. The bar 104 is positioned against the side of a toothed wheel 113 which has a circular hub 114 at the back, and the bar 104 is provided with two rollers 115 and 116 which engage the inner surface 117 of the hub 114, and the outer portion of the bar is formed with a slot 118 having an inclined outer surface 119 which slopes downward in the position shown in Figure 2, and a roller 120 is 55 mounted between the outer surface 121 of the part 114 and the surface 119, and it will be noted that as the clutch bar is moved upward the roller will jam between these two surfaces and thereby form a positive lock, causing the wheel 113 to move upward therewith, and with the teeth of the wheel 113 meshing with the teeth of a gear 122, the gear 122 will rotate with each upward movement of the clutch bar 104. The 60 roller 120 is resiliently held downward by a spring 123 engaging the roller through a pin 124, and the spring is held in a recess in a member 125 on the upper side of the bar 104. This is a typical arrangement of the clutch, however, it 65 will also be understood that the clutch may be 70 75

provided with two rollers, similar to the brake shown in Figure 3, and it will also be understood that the brake may be formed with only one roller, similar to the clutch shown in Figure 2, as either design may be used for either the clutch 5 or brake.

It is necessary to hold the shaft 112 so that it cannot move backward, and so that it will only move with the movement of the clutch and, therefore, a brake is provided, as shown in Figures 1 and 3, and the brake is formed with a bar 126, one end 127 of which is mounted on the shaft 112 through a yoke with a block 128 and a bolt 129, and the opposite end is held on a pin or screw 130, as shown in Figure 3. This bar also 15 cooperates with a wheel 131 having a cylindrical hub 132 with rollers 133 and 134 engaging the inner surface, and with rollers 135 and 136 engaging the outer surfaces, and an inclined surface 137 of the bar 126. A light spring 138 is 20 provided between the rollers 135 and 136, and a slightly heavier spring 139 which is held in a cap 140 on the bar 126 engages the larger roller, and it will be noted that these springs hold the rollers in engagement with the respective surfaces, thereby 25 preventing the wheel 131 and the shaft 112, upon which the wheel is fixedly mounted, rotating in a counter-clockwise direction, and permitting rotation thereof in the opposite direction and only as moved by the clutch, the clutch preventing movement in the opposite direction when not in use. It will be understood that, as hereinbefore stated, this brake may also be formed with one roller instead of two, and also that the clutch 30 may be provided with two rollers, if desired. 35

The oil pump 6 is formed with a cylinder 141 and a plunger 142, with the upper end of the plunger held in a bearing 143, and with the part supported on the inside of the main frame in a bracket 144, and held by bolts 145 and 146. The 40 plunger 142 is operated by an eccentric 147 through an arm 148, the lower end of which is pivotally attached to the plunger 142 through a collar 149 fixedly mounted on the plunger, and provided with a pin 150, which is pivotally held 45 in a hub at the lower end of the arm. It will be noted that as the eccentric moves the arm upward and downward it will move the plunger upward and downward, and as the plunger moves upward it will draw liquid into the cylinder 50 through a check valve 151 at the lower end, and as it moves downward it will close the check valve 151 and unseat the check valve 152, thereby forcing the liquid through a tube 153 to a pan 154, in the upper part of the machine. The machine is provided with a drip pan 155 at the lower end, and a pump supply tube 156 extends downward into the drip pan, and this is provided with 55 openings 157 through which oil may be drawn into the cylinder so that all oil dripping downward in the machine will be adapted to be drawn upward, and pumped back to the pan at the upper end. The tube 156 may be provided with filtering material 158 for straining or cleaning the oil, however, it will be understood that any means 60 may be provided for cleaning the oil. The pan 154 may be supported in brackets 159 and 160 in the upper part of the machine, and this may also be provided with an overflow tube 161 which will take oil back to the pan 155, however, it will 65 be understood that the pan 154 may be provided with openings 162 which may be located at different points, so that oil will drip from the pan upon the different operating parts of the machine, and these openings may be located at any 70 75

points desired. It will be understood that a pump of any other type or description may be used, or any means may be provided for automatically elevating the oil and feeding it back upon all of the moving parts of the machine.

It will be understood that other changes may be made without departing from the spirit of the invention. One of which changes may be in the general design or arrangement of any of the parts, another may be in the use of a clutch or brake of any other type or design, and still another may be in the use of bearings, cams, eccentrics, or other operating parts, in combination with the parts shown and described, in order to complete the operation of this machine or improve the same.

The construction will be readily understood from the foregoing description. In use the machine may be provided as shown and described, and it will be understood that this application only covers the improvements in the parts and, therefore, does not describe many parts of the machine, such as the front feed discs, needle bar, looper, and thread feeding mechanism. With the machine constructed as shown and described, it will be operated by a belt or the like over the belt wheel 28, and with thread placed through the needle 163 and threaded through the remaining parts of the machine, material may be fed through the feed discs and sewed at comparatively high speed.

As the machine operates, the main shaft 2 rotates, and the eccentrics and cams move the different parts. The eccentric 31 moves the block 32 upward and downward, and this, in turn, moves the looper frame 3 with an oscillating movement, with the lower corner moving backward and forward on the rocker 57 and with the upper backward corner sliding backward and forward on the block 51. This operates the looper 36 with an oscillating movement, and at the same time the looper is turned by the shaft upon which it is mounted, which is connected through the member 2 to the ball 46 in the cam groove 41. During this movement, the cam 76 moves the needle bar yoke backward and forward, and whereas the needle bar yoke was formerly mounted only on the bar or shaft 73, it is now provided with bearings at the lower end, with the lower end sliding on a stationary shaft 74. Without the shaft 74 the yoke would have a twisting movement about the shaft 74, causing wear in the bearings in the frame and, therefore, with the lower end slidably held, this twist is entirely eliminated, and the yoke has a positive backward and forward movement. It is thought that this will be sufficient to compensate for the high speed of the machine, however, it may also be provided with a sliding block 77, as shown in Figure 8, which will further diminish wear between the eccentric and the surfaces of the yoke.

The looper frame normally develops considerable wear at high speed at the upper end of the frame, as the thrust of the looper in both directions causes considerable wear against the frame parts, and this causes play, which is objectionable, so that all engaging parts of the looper shaft have been increased and provided with collars to increase the wearing surfaces and, therefore, eliminate this wear. By the same means, considerable wear develops between the fork at the upper backward corner, and the bolt upon which it slides and, therefore, the block 51 has been inserted between these parts, which increases the bearing surfaces, and diminishes

the wear. Heretofore the cam 31 has operated against the flat surfaces of the parts 29 and 30, and with this oscillating movement the cam, engaging at two points only, wears these surfaces considerably, so that considerable play develops and, therefore, the block 32 has been inserted, which provides continuous engagement with the cam or eccentric surface, and an easy sliding movement between the block and fork of the looper frame. The lower ends of the fork 10 are also provided with a bolt 35, by which any wear that may develop may be taken up. It has also been found that the lower forward corner of the looper frame wears considerably on the pin of the rocker 57 and, therefore, the boss 56 has been provided on the side of the frame to lengthen the bearing and reduce this wear to a minimum. The length of the bearing 59 has also been increased to provide more bearing surface and reduce the wear between these parts.

The spring 85 has normally been positioned in the lower part of the frame, and this has made it necessary to use a relatively short arm in place of the arm 92, and operators have found it objectionable because the short arm requires considerable strength on the downward pull of the chain 93, whereas by arranging the spring between the bars 82 and 83 it is possible to double the length of the lever 92, and thereby reduce the force necessary to operate the lever to move the feed disc arm 81 outward. The shaft has also normally been mounted directly in bearings in the frame, and although these were satisfactory for the speed at which the machine was designed to operate, these bearings develop considerable play at the high speed which is now required of the machine and, therefore, it has been found necessary to provide space in the frame for ball bearings, so that the main shaft may be mounted in ball bearings, as shown. With these improvements in the operating parts of this machine, it is possible to operate the machine at about twice the normal speed without increasing the size or external appearance, and by using substantially all of the original parts thereof.

Having thus fully described the invention, what I claim as new, and desire to secure by Letters Patent, is:

1. In a sewing machine for fur, and the like, of the type having feed discs for holding the material, a needle bar operated by a needle bar yoke, a looper operated by a looper frame, a feed disc arm resiliently holding one of the feed discs, and a main driving shaft with suitable eccentrics and cams for operating the respective parts, and in which the looper frame is provided with a fork having flat surfaces positioned to be engaged by an eccentric on the main shaft; the combination of a sliding block on the said eccentric operating the looper frame in which the block is formed with flanged grooves at the sides slidably engaging the sides of the fork of said frame.

2. The combination with a machine as described in claim 1 of a main frame forming a housing in which the parts are mounted, said housing characterized by extensions at the sides, providing mounting for ball bearings in which the main shaft is rotatably mounted.

3. A machine as described in claim 1, in which the forward lower corner of the said looper frame is pivotally mounted on a looper frame rocker through a bearing, and characterized in

that an extension is provided at the side of said looper frame increasing the length of said bearing.

4. A machine as described in claim 1, in which the forward lower corner of the said looper frame is pivotally mounted on a looper frame rocker through a bearing, and characterized in that an extension is provided at the side of said looper frame increasing the length of said bearing, and also in which the said looper frame rocker is pivotally mounted through a bearing, and further characterized in that the bearing is extended, providing greater bearing length therein.

15 5. A machine as described in claim 1, characterized in that the feed disc arm is resiliently held inward by a spring positioned in alignment therewith.

20 6. A machine as described in claim 1, in which the feed disc arm is slidably mounted on two rods and resiliently held inward by a spring between the two rods.

25 7. A machine as described in claim 1, in which the feed disc arm is slidably mounted on two rods and resiliently held inward by a spring between the two rods, and characterized in that the said feed disc arm is moved outward by a bell crank positioned on a shaft adjacent the back of the machine with a comparatively long 30 lever arm extending forward from said bell crank and through which the bell crank is operated.

8. A machine as described in claim 1, characterized in that one of the feed discs is rotated by an intermittent motion and said rotating means is operated by an eccentric through a clutch and characterized in that the clutch is formed with a roller between a wheel rim and an inclined surface, providing a wedge action.

9. A machine as described in claim 1, characterized in that one of the feed discs is rotated by an intermittent motion and said rotating means is operated by an eccentric through a clutch and characterized in that the clutch is formed with a roller between a wheel rim and an inclined surface, providing a wedge action, and further characterized in that the said intermittent drive is restrained from backward movement by a brake formed with a roller positioned between a rim wheel and an inclined surface, also providing a wedge action.

10. A machine as described in claim 1 in which the said looper is mounted on a shaft in the said looper frame, and characterized in that friction collars are provided between the moving parts of said looper mounting mechanism and the looper frame.

11. The combination with a machine of the class described, of a clutch operating a part of said machine with an intermittent motion, char-

acterized in that the clutch is formed with a bar pivotally and slidably mounted, through a sliding block, on a shaft having a toothed wheel thereon, in which the said toothed wheel is provided with a cylindrical hub cooperating with 5 said bar, rollers pivotally mounted on said bar engaging the inner surface of said hub, said bar adapted to be raised intermittently from the outer end thereof, said bar having an inclined surface positioned outside of the periphery of the hub on said toothed wheel, a roller positioned between said inclined surface and the periphery of said wheel, and means resiliently holding said roller in engagement with said surface and wheel.

12. The combination with a machine of the 15 class described, of a clutch operating a part of said machine with an intermittent motion, characterized in that the clutch is formed with a bar pivotally mounted on a shaft having a toothed wheel thereon, in which the said toothed wheel 20 is provided with a cylindrical hub cooperating with said bar, rollers pivotally mounted on said bar engaging the inner surface of said hub, said bar adapted to be raised intermittently from the outer end thereof, said bar having an inclined 25 surface positioned outside of the periphery of the hub of said toothed wheel, a roller positioned between said inclined surface and the periphery of said wheel, means resiliently holding said roller in engagement with said surface and wheel, a second larger roller also positioned between said inclined surface and the periphery of said wheel, and means resiliently holding said second roller in 30 engagement with said inclined surface and wheel.

13. In a sewing machine for fur, and the like, of the type having feed discs for holding the material, a needle bar operated by a needle bar yoke, a looper operated by a looper frame, a feed disc arm resiliently holding one of the feed discs, and a main driving shaft with suitable eccentrics and 40 cams for operating the respective parts, and in which the needle bar yoke is formed with flat surfaces at each end; the combination of a sliding block slidably engaging said flat surfaces and rotatably mounted on an eccentric operating 45 said needle bar yoke.

14. In a sewing machine for fur, and the like, of the type having feed discs for holding the material, a needle bar operated by a needle bar yoke, a looper operated by a looper frame, a feed disc arm resiliently holding one of the feed discs, and a main driving shaft with suitable eccentrics and cams for operating the respective parts, and in which said needle bar yoke slidably operates backward and forward and is mounted upon a shaft at the upper end, the combination of a second shaft slidably mounting the lower end thereof.

THOMAS C. MLADINICH. 60
